No. 832,853.

PATENTED OCT. 9, 1906.

H. A. GADSDEN.
CAR VENTILATING APPARATUS,
APPLICATION FILED JUNE 20, 1904.

UNITED STATES PATENT OFFICE.

HENRY A. GADSDEN, OF LONDON, ENGLAND.

CAR-VENTILATING APPARATUS.

No. 832,853.

Specification of Letters Patent.

Patented Oct. 9, 1906.

Application filed June 20, 1904. Serial No. 213,310.

To all whom it may concern:

Be it known that I, HENRY A. GADSDEN, a citizen of the United States, residing at London, England, have invented a certain new 5 and useful Improvement in Car-Ventilating Apparatus, of which the following is a specification.

The object of the present invention, stated broadly, is to provide means for the ventilation 10 of railway-cars and other vehicles.

More specifically, the object of the invention is to provide an efficient means of the character stated through the operation whereof air will be passed in a continuous 15 cycle through the car or other vehicle, pure air being introduced at a suitable point and the passage thereof at such point being utilized to assure not only the ingress of pure air to the car, but also the egress of air which has 20 become impure.

A further object of the invention is to accomplish this result in a simple and economical manner, so as not to add substantially to the cost of production of a new car or to 25 add substantially to the cost of embodying the invention in a car already in use.

A further object of the invention is to so arrange the apparatus as to make the same substantially automatic, although mechanism 30 may be provided for adjusting to a nicety the quantum of air fed to the interior of the car from the outside thereof.

A further object of the invention is to provide for the removal from air fed to a car of 35 dust and other impurities and also, if desired, to not only purify, but likewise warm or cool, such air before permitting the same to pass to the interior.

A further object is to provide apparatus of 40 the character described which shall not impose additional weight upon the car near the upper portion thereof, the effect whereof would be to increase dangerous swaying, but to add substantially to the stability of the 45 car by locating the additional weight below the center of gravity—*i. e.*, at or about the level of the car-floor.

In carrying out the invention in a form applicable to a type of railway-car commonly 50 employed in the United States, this type being selected merely for the purpose of the present disclosure and not as limiting the application of the invention, I employ a substantially continuous air-passage extending 55 from one end of the car to the other and pro-

vided at each end with a hood or funnel for the ingress and egress of air. Such hood is preferably adjustable so as to be directed either forward or rearward and may be arranged on top of the car, connecting with vertical portions of the air-passage, which, if desired, may be arranged just inside the front and rear car-walls. These vertical portions are connected by a horizontal portion, which may be arranged either above or below the 60 car-floor, as desired, and in such horizontal portion may be arranged a receptacle or receptacles for water or other fluid and also, if desired, deflectors whereby the air passing through such passage will be forced into contact with such water. The upright portions of the air-passage at either end of the car are provided with adjustable valves, whereby the quantum of air passing through the passage may be nicely regulated. These valves 65 may be arranged at any suitable height from the car-floor, but preferably somewhat above the height reached by the heads of the occupants of the car. The movement of the car is relied upon to force a quantity of 70 air through the hood or funnel at one end of such car, this hood or funnel being preferably protected by means of a screen of woven wire, foraminated material, or other suitable device. The air on passing into 75 such passage is forced the entire length of the car, and a portion thereof thence out of the passage through one of the valves above mentioned and into the body of the car, where it passes forward under pressure and 80 the influence of the suction at the receiving end of the passage, so as to pass again into 85 such passage. The quantum of air thus fed such passage into the car is determined by means of the valve, preferably at the delivery end of such passage, and this may be arranged so as to deflect from the passage and into the interior of the car the entire body of air received at the forward end of the 90 passage, or such smaller portion thereof as 95 may be desired, the remaining portion being permitted to pass from such air-passage to the outside atmosphere through the hood or funnel at the other end of the car. At a suitable point or points in the air-passage, between the forward and rear ends thereof, I 100 prefer to arrange an air-purifying tank or tanks and to employ in connection with these air-deflectors for the purpose above referred to. In practice either one or more 105

of said air-passages may be employed, and the present invention is not to be regarded as limited in this respect, although I shall, for the purpose of disclosing such invention, describe an embodiment wherein two such passages are used, one on either side of the doorways at either end of the car.

The invention is illustrated in the accompanying drawings, in which—

- 10 Figure 1 is a sectional view of a car equipped with my improved ventilating apparatus, the car-body being shown in dotted lines. Fig. 2 is a cross-section on the line 2—2, Fig. 1. Fig. 3 is an enlarged sectional view of a portion of the air-passage. Fig. 4 is an enlarged detail illustrating a means of adjustment of the valves in the upright portions of the air-passage; and Figs. 5, 6, and 7 are central sections of the air-passage, illustrating, however, modifications of the construction shown in Fig. 1.

Referring to the drawings, in which similar letters of reference denote corresponding parts, and premising with the statement that since where more than one air-passage is employed they will be substantially the same in construction, and therefore but one need be described in detail, A designates the horizontal portion of the air-passage, here shown as arranged just below the floor B of the car C, although it may be arranged above such floor, if desired. In Fig. 1 this passage is shown as equipped with the central air-purifying tank D, having silt-cock d and of such area as to permit a suitable quantity of water or other fluid d' to be carried therein. Over this purifying-tank the air-passage A is provided with deflectors a a', which may, if desired, be adjustable, a suitable clamping mechanism—such, for instance, as that hereinafter described—being employed for securing such deflectors in position to so act upon the air passing through said passage as to bring the same in contact with the water or other fluid in said tank D.

E F designate, respectively, the forward and rear upright portions of the air-passage. These, as shown, are connected at their lower ends with the horizontal portion A of such passage and may be arranged either within or without the front and rear walls of the car. The upper ends of these upright portions E F terminate in funnel-shaped hoods G, the ends whereof may be provided with screens g for the purpose of excluding coarse impurities from the air passing into said hoods.

H I designate, respectively, valves carried by the forward and rear upright portions E F of the air-passage. These are here shown as hinged at h and arranged (when in closed position) over openings or ports h' i', formed in the upright portions E F. Any suitable means may be employed for adjusting these valves—such, for instance, as the mechan-

ism illustrated in Fig. 4, comprising the operating-handle h², the slotted segment h³, and jam-nut h⁴.

In Figs. 5, 6, and 7 are illustrated certain modifications of the construction of the horizontal portion A of the air-passage with respect to the air-purifying tank above referred to. In the construction illustrated in Fig. 5 I have shown such horizontal portion A as provided with two separated tanks L and deflecting wings or vanes l to assure the passage of the air close to or in contact with the fluid l' in said tanks. In Fig. 7 a slightly different arrangement of the parts is illustrated, the horizontal portion of the air-passage being here shown as above the car-floor and provided at each end with tanks P Q, with which the vertical portions of the air-passage also connect, such tanks being provided with partitions b q and ports for ingress and egress of water. If desired, however, instead of having a single tank at approximately the center of the car or two separated tanks, the horizontal portion A of the air-passage may be adapted to receive and carry the water or other fluid substantially throughout its entire length. Where this is done, however, it is obvious that means must be employed for preventing the accumulation of water at one or the other end of the car, as would occur on certain grades, for the effect of this would be to substantially seal the passage against the ingress and egress of air. The end may readily be attained in the manner illustrated in Fig. 6, wherein I have shown an elongated tank M, provided with partitions m at suitable intervals extending substantially above the water-level, and therefore precluding the passage of the entire quantity of water in such continuous tank to either end of the air-passage and the consequent sealing of such passage.

If desired, the bottom of the horizontal portion A of the air-passage, whether provided with a tank or tanks or partitions or not, may be covered with a layer of felt or other absorbent material, and this may be kept moist by a drip-tank, for instance, suitably located. Such a layer of absorbent material will answer the purpose above described and in addition possesses the advantage of being substantially independent of variations in the grade of the road-bed.

A car equipped with the apparatus above described may or may not be provided with the usual ventilators just below the roof. Whether provided or unprovided with such ventilators, it is obvious that to adequately ventilate the car (and by this I mean not only to permit the egress of impure air, but also to assure the ingress of pure air) such ventilators are wholly insufficient, and the successful operation of the apparatus of my invention is entirely independent of them.

In the use of the apparatus above described

the movement of the car causes the outside air to be forced through the funnel G and thence into the upright portion E of the air-passage, thence through the horizontal portion A thereof and through or over the fluid in the purifying-tank, and thence to the upright portion F of such air-passage, where the same is acted upon by the valve I to permit the passage of the whole or a portion of such air back into the car through the port or opening i'. Where but a portion of such air is permitted to pass into the interior of the car, the remainder passes by such valve I and out through the exhaust-hood G. Such portion of the air as is permitted to pass into the interior of the car through said port or passage i' moves forwardly within the car, becoming associated meanwhile with the impure air already in such car, and the whole, or 20 a substantial portion thereof, is drawn, by reason of the passage of air through the upright portion E of the air-passage, through the port or passage h' and thence downward and rearward through the portions E and A of the air-passage, where such combined pure and impure air is again purified by means of the fluid in the purifying-tank D. Of course in the passage of the air from the port i' to the port h' a certain portion of such air will 25 escape through orifices other than said port h'—as, for instance, through windows or other openings. This, however, does not materially affect the cycle of movement of the air originally introduced through the forward hood G, but permits a constant and uniform distribution of pure air in a manner which may be characterized as "a cycle of ventilation."

Any suitable means may be employed for 40 flushing or washing out the horizontal portion of the air-passage. Thus, if desired, the same may be provided with a port at each end adapting it to be quickly and thoroughly cleansed of silt and other impurities when the 45 car is not in use by directing a stream of water therethrough.

Of course, should the movement of the car result in the passage of too great a quantum of air through the air-passage and the consequent introduction of too great a quantum of air into the interior of the car, this difficulty may be overcome by the adjustment of the rear valve I, the movement of that valve toward and from its seat operating, as above indicated, to regulate the quantum of air passing to the interior of the car, the remainder of such air being permitted to pass from the vertical portion F of the air-passage and thence out through the rear hood G.

Having now described my invention, what 60 I claim as new therein, and desire to secure by Letters Patent, is as follows:

1. The combination with a car, of a continuous air-passage comprising a pipe running lengthwise of the car and extensions at the 65 ends of said pipe open at their ends to the atmosphere, said extensions each having an aperture to the interior of the car, an adjustable valve associated with the aperture in one of said extensions for directing air flowing 70 down said extension past the aperture therein, and an adjustable valve associated with the aperture in the other of said extensions for directing through the aperture in said extension a portion of the air flowing through 75 said lengthwise pipe and up the extension and the remainder of said air past the aperture to the open end of the extension, substantially as set forth.

2. The combination with a car, of a continuous air-passage comprising a pipe running lengthwise of the car adjacent to the floor thereof, air-purifying devices in said pipe, vertical extensions at the ends of said pipe open at their ends to the atmosphere, said 85 extensions each having an aperture to the interior of the car, an adjustable valve associated with the aperture in one of said extensions for directing air flowing down said extension past the aperture therein, and an adjustable valve associated with the aperture in the other of said extensions for directing through the aperture in said extension a portion of the air flowing through said lengthwise pipe and up the extension and the remainder of said air past the aperture to the 90 open end of the extension, substantially as set forth.

3. The combination with a car, of a pipe 100 extending the length thereof, vertical extensions one at each end of the pipe and each having an always-open air-collecting funnel and an aperture to the interior of the car, and an adjustable valve for each aperture hinged at the upper edge of the aperture and opening 105 into the vertical extension, whereby air may be drawn from the car through the aperture in the vertical extension at the forward end and returned to the car through the aperture at the other end, substantially as set 110 forth.

This specification signed and witnessed this 11th day of May, 1904.

HENRY A. GADSDEN.
